WALL PAPER OR SIMILAR ARTICLE

Filed Sept. 2, 1931

INVENTOR

EMILE ERICSON

BY HIS ATTORNEY

Frank J. Fitch

UNITED STATES PATENT OFFICE

EMILE ERICSON, OF PELHAM, NEW YORK, ASSIGNOR TO PRAGER CO., INC., A CORPORATION OF NEW YORK

DESIGN FOR WALL PAPER OR SIMILAR ARTICLE

Application filed September 2, 1931. Serial No. 40,998. Term of patent 3½ years.

To all whom it may concern:

Be it known that EMILE ERICSON, a citizen of the United States, residing at Pelham, in the county of Westchester and State of New York, has invented a new, original, and ornamental Design for Wall Paper or Similar Article, of which the following is a specification.

In the accompanying drawing:—

The figure is a surface view of a piece of wall paper or similar article showing the design. The piece of wall paper is shown in two sections, namely, an upper section and a lower section. The lines EF of the upper

section are intended to coincide with the line EF of the lower section. In other words, the design is complete from the line AB of the upper section to CD of the lower section. This area represents one complete unit of the design which repeats at the sides. The design extends the complete width of the strip of wall paper.

I claim:—

The ornamental design for wall paper or similar article as shown and described.

In testimony whereof I affix my signature.

EMILE ERICSON.
